UNITED STATES PATENT OFFICE.

JOSEPH H. ADAMS, OF FLATBUSH, NEW YORK, ASSIGNOR TO THE TEXAS COMPANY, OF HOUSTON, TEXAS, A CORPORATION OF TEXAS.

APPARATUS FOR THE CONVERSION OF LIQUIDS, FLUIDS, AND OILS.

1,320,727.

Specification of Letters Patent.

Patented Nov. 4, 1919.

Application filed March 29, 1915. Serial No. 17,699.

To all whom it may concern:

Be it known that I, JOSEPH H. ADAMS, a citizen of the United States, residing at Flatbush, in the county of Kings and State 5 of New York, have invented a new and useful Apparatus for the Conversion of Liquids, Fluids, and Oils, of which the following is a specification.

Description.

10

My invention relates broadly and primarily to an apparatus for converting high boiling point petroleum oils and distillates as well as those of the aromatic series into 15 more volatile products resembling lower boiling oils of the gasolene, benzin, naphtha type and larger yields of benzol and other low specific gravity products of the aromatic group to augment the gradually diminishing supply of the natural product, or that 20 which is presently obtained from crude petroleum and coal tar by the commonly practised methods of fractional distillation, in order to meet the increasing demand for 25 these products.

It is intended that this conversion apparatus shall be available for the transformation of oils and oily vapors of the hydro-carbon series and for all other conversion 30 and reactionary methods and practices for which it may be adapted.

One object of this invention is to provide a suitable apparatus in which to carry out, in a continuous manner, a process for bringing about the conversion and transformation of oils and oily vapors by means of externally applying a high degree of heat to a chamber, the whole or part of which is composed of heat enduring material, and while 35 containing hydro-carbon oils or oily vapors under vapor pressure, heating the walls of the chamber to a temperature of sufficient intensity to crack and convert the same into oils or petroleum and coal tar oils and spirits 40 different and possibly more valuable than the original untreated oil.

This invention is based on the facts that hydro-carbon oils and vapors of oil distillates can be successfully and commercially 50 converted into those of lower specific gravity and boiling points, by means of properly applied intense heat and high vapor pressure, without unduly transforming them into a large quantity of fixed gases as more

fully set forth in my co-pending applications 530,852, December 1, 1909, 618,011, March 30, 1911, and 879,907, December 31, 1914. The products produced by the transformation differ in character from the original material and for certain purposes are 60 more useful and more valuable.

This invention comprises an apparatus capable of being constructed at a moderate cost, and so designed as to enable skilled workmen to readily operate the same at a 65 high rate of efficiency in lowering the boiling points of various grades of hydro-carbon oils.

Another object within the contemplation of this invention is to provide an apparatus 70 capable of some variation in the mode of operation, so as to adapt the same to the treatment of different oils, where simple and inexpensive parts and features can be arranged and correlated to render complete 75 an organization or system of continuously converting hydro-carbon oils and oily vapors on a common basis, in an apparatus of practical and enduring nature, wherein the more valuable materials such as naphthas, 80 gasolenes, benzols and toluols of low specific gravities can be converted from oils of less value and higher boiling points.

Other objects and advantages of my invention will be set forth hereinafter, and 85 the novel features thereof set forth in appended claims.

In order that this invention may be the more fully disclosed and otherwise made wholly comprehensible to those skilled in the 90 art, drawings typical of the many possible embodiments thereof have been appended hereto, as a part of this disclosure, and in such drawings like characters of reference denote corresponding parts throughout the 95 several views of which:—

Figure 1, is an elevation and partly sectional drawing of the collective apparatus embodying certain aspects of this invention wherein heat of intense temperature is applied to oil and oily vapors while under vapor pressure, and also showing details of the various parts, and which, for all purposes of description, will afford a clear and well defined view of the several features 100 comprising the converting apparatus and its correlated pumps, tanks and containers.

Fig. 2 is a sectional view at the top of a

furnace, shown to illustrate a common form of heater which may be adapted for this work, and also the correlated local parts of the heating and oil or oily vapor cracking apparatus.

Fig. 3 shows more clearly a form of release pop valve and oil vapor and liquid collector.

Fig. 4 is a top view of the cracking chamber crown, to the under side of which the cracking plate is attached, and which is mounted over the furnace or heater.

Fig. 5 is a partial or segmental plan of the cracking plate or medium which, when brought to the proper and required intense heat by means of the underlying furnace, brings about the desired conversion, as more fully set forth in the following description, and:—

Fig. 6 is a partly sectional view of the liquid and vapor dome base showing the circular rows of overflow pipes, liquid receptacle and discharge pipe.

The reservoir tank, A.

Referring now to Fig. 1, the source of supply A, can be somewhat elevated with respect to the converter C—D, so that the gravitating tendency of the oil may augment its flow into the converter under the influence of the contained weight of oil, or the ease with which it may be withdrawn and forced into the converter by means of pump 5.

The fluid oil may be supplied to the container A, through the pipe 1, while at the same time displaced air from the tank can escape through vent pipe 2, at the top of the container.

For obvious reasons it is best to pre-heat the oil before it is admitted to the converter C—D, so that the heat in that part of the apparatus may be conserved for the more important function of "cracking", splitting the molecules of, and rapidly vaporizing the converted oil, and therefore the heating system B, is provided and interposed between the source of supply and the converter, wherein the oil to be treated can be brought to any desired temperature.

This pre-heater may be of any suitable type, but preferably provides a continuously rising coil 15, contained within the hot oil receptacle 16, where the overflow hot oil from the dome D, supplied through pipes 24 and 25, can be utilized to heat the incoming cold oil within the coil, or the pipe coil 17, located in stack 50, can be arranged to utilize the waste heat from the furnace C, to pre-heat the inflowing hot oil to the converter C—D.

The oil to be so heated is preferably admitted to the bottom of the coils and progresses upwardly in its flow, so that any bubbles or vapor may rise and readily es-

cape and not form air locks to retard the flow or oil into the converter.

The oil converting receptacle, C—D.

The drawing shows one of the many diverse forms which the converter C—D, may assume, and such converter here shown comprises a cracking chamber 18, of oil containing capacity, having a crown 49, and a heat enduring bottom plate 19, located directly over a heating medium or furnace C.

The chamber 18, is connected by a pipe or neck 20, directly with an inclosed expansion dome D, intended to contain both liquid and vapor, and closed at the top by means of a cap 21.

A gage glass 22, and thermometer 23, can be arranged on dome D, for the inspection of oil quantities and temperatures, which are in part regulated by the flow of oil through supply pipe 8, and precision valves 9, and in part by the overflow of oil through pipes 24 and 25, pre-heater tank 16, pipe 27; and into hot oil receiving tank 26.

A glass gage 28 is arranged on column 29, in order to inspect the location of oil in that part of the system.

The furnace C, is provided and located under the liquid and vapor dome D, and cracking chamber 18, as a means of generating intense heat by known methods of gas, fuel oil, coal or electricity; and this furnace is supported on legs or piers, if necessary, so that in the use of gas or fuel oil, access can be more readily had to the feed valves and controllers which may be located in the underlying pipe system.

A pyrometer element 30, is arranged to extend through the walls of the furnace C, in order that temperatures may be determined therein, which, in this conversion system, is a very important feature. A port 95, is located in the furnace wall, for inspection purposes, which same is closed with a suitable fire brick plug, provided with a handle.

Inasmuch as the vapors rising into and filling the upper part of the expansion dome D, may, at any time, be so rapidly evolved as to exert undue or spasmodic pressure, I have placed a collecting trap tank 31, and release pop valve 32, in close relation with the upper part of the dome, by means of the pipes 33 and 29, so that any undue or sudden pressure above a given number of pounds necessary to carry on the process work under normal conditions, will cause the release pop 32, to act rapidly and relieve the excessive pressure into goose neck 120 pipe 34, condenser head 37, and the coils 42, of apparatus E.

A feature of primary importance is the means for externally applying heat of intense temperatures to the heat enduring, or

cracking plate 19, for the purpose of bringing about a more or less complete conversion of oil.

Preferably this feature is operated by gas or fuel oil, and comprises one or more jets 44, to which elements of combustion are fed through pipes 78 and 79, and thereafter forced into an inclosed furnace C, composed preferably of a metal shell, or container 45, 10 lined with fire brick 46, and asbestos or magnesia filling 47, which together are intended to retain the heat as long as possible, for the purpose of maintaining the plate 19, at the proper and uniform temperature for 15 more or less perfect conversion.

In the show form, this furnace C, with its intake pipes 44, and outlet or exhaust flue 48, passing through stack 50, is made up in circular form, and partially filled with a 20 checker work of fire brick 46, to properly heat the round plate 19, located at the top of the furnace in the form of a cap; and while the design of heater may be varied to conform with the different styles of converters which could be made, this form is well 25 adapted for the economical use of gas and liquid fuels, to generate the required intense heat, and especially for operating in the oil and gas regions, where the fuel cost is 30 low.

When operating on oils for the purpose of converting them, it is necessary to localize the heat so as to prevent its spreading in a lower degree of intensity than is necessary 35 to effectually "crack" the oil, and to this end, in the embodiment of the apparatus, I have provided a crown 49, to which the cracking plate 19, is made fast with bolts drawn against a gasket at its outer edge, and spaced 40 them so that only a thin layer or body of oil contained in the chamber 18, comes in close proximity to the intensely heated surface of the plate 19, which, as shown at Fig. 5, is provided with slotted holes 51, having parallel edges radiating from the center of the 45 plate, so that as expansion or contraction takes place in the plate 19, a means is provided to protect the crown 49.

A more comprehensive idea of this crown 50 can be had from Fig. 4, wherein three ports 52, and a number of oil supply pipes 53', are definitely located to facilitate operation.

This drawing shows the radiating ribs 54, which help to strengthen that part of the 55 apparatus.

The sight tubes 55, provide a means of inspecting the condition of the cracking plate 19, or the molten metal 19', (Fig. 2) while the converter is in operation; and also 60 affords a port through which pieces of metal or alloy can be placed within chamber 18, preparatory to its becoming melted on plate 19.

To protect plate 19, from burning out, or the destruction of oil over its surface, with 65 a consequent deposit of carbon and the more

or less complete transformation of oil into fixed gases, with large commercial losses, I employ a metal or alloy having a melting point consistent with the required "cracking" temperature for the oils to be treated; 70 which, when brought to the proper degree of heat becomes a semifluid metal 19', (Fig. 2) flowing over the top surface of the plate 19, where it may be seen through inspection sights 55, if there is clear oil in cracking 75 chamber 18, and remaining so during the process of conversion, when the furnace heat is maintained at the proper degree of intensity.

In this manner the oil does not come in 80 direct contact with the plate 19, but is affected by the molten metal which protects the upper surface of the cracking plate from the undesirable and destructive accumulation of carbon resulting from the process 85 of "cracking."

Alternately, and for the treatment of very light gravity oils, the molten metal can be omitted from the apparatus, when in operation, so that the oil may come in direct contact with the intensely heated surface of plate 19, and the choice between these two methods of oil contact with the heat is largely a matter of judicious oil converting 90 practice over which no set rules can govern. 95

In order to prevent furious agitation within chamber 18, and dome D, while the converter is in operation, baffle plates 56, are located within the neck pipe 20, and made fast to rod 57, which rod extends through 100 cap 21, of dome D, and to which it is attached by means of lock nuts, then the joint is properly sealed with a gland or stuffing box 80.

The baffle plates located in this manner 105 will overcome any undue geyser action or oscillation of the oil while being subjected to the intense heat within chamber 18.

Owing to the high temperatures employed 110 in the conversion process, and the consequent volatilization of unconverted oils treated under ordinary atmospheric conditions, I have, by a series of valves and collecting trap tanks, provided means for carrying on this process under vapor pressure of several atmospheres, if found necessary, by setting release pop valves to operate at certain pressures, as indicated by gages 41 and 87, both for the release of vaporized oil from the top of dome D, through valve 32 and 115 tank 31, and liquid oil from the bottom of dome D, through pipe 24, valve 58, in tank 19, from which it flows through pipe 25, and valve 62, and is collected in hot oil tank 26.

In this manner I am able to reduce the 120 undesirable vaporization, without conversion, to a minimum, and as a consequence the oils and oily vapors are, in a large proportion, "cracked" and otherwise converted 125 in character without, however, transforming 130

them into the undesirable olefins and ethylenes, which are offensive in odor and uneconomical for commercial purposes.

In addition to the intense heat and high vapor pressure employed for the purpose of conversion, I also may use superheated steam forced into the body of oil or oily vapors through pipe 60, and small jets or nozzles 61, and which are provided to inject steam 10 with the oil at its point of entry into the cracking chamber 18.

A valve regulates the supply of steam in proportion to the amount of oxygen required to combine with a certain portion of carbon 15 contained in the oil and which is cracked out ordinarily by the intense heat, and also to add hydrogen to the oil or oily vapors to assist in lowering the boiling point and increase the yield of converted products.

20 In this manner the product of conversion is freed from a portion of undesirable carbon, which would otherwise accumulate in the cracking chamber and in time retard the progress of oil transformation.

25 During the operation of the process, the raw non-converted oils will be relieved of a certain portion of free carbon, of which they may be in part composed as well as some of the foreign substances which it may 30 be desirable to eliminate, and, through the agency of steam, hydrogen will be added.

Some of the refuse will be deposited on the cracking plate 19, or the molten metal 19', above it, and from which it can be 35 moved from time to time by cooling the furnace, withdrawing the oil from the cracking chamber 18, and dome D, then opening ports 52, which are more clearly shown in Figs. 2 and 4, and with a narrow scraper, 40 or long slicing chisel, clearing the surface of the plate or the metal.

In Fig. 3, a detailed drawing shows a form of vapor or liquid trap tank and release pop valve wherein 59, is the container 45 or tank provided with a tightly fitting cover 59', held in place by means of bolts. A bottom plate 59'', is provided and attached in a similar manner so as to make a perfectly tight inclosure.

50 The release pop valve 58, is arranged centrally on pipe 24, and the spring 58'', can be regulated for various pressures by means of the rod and cross head 58', which projects through the cover 59', and is properly 55 sealed by a gland or stuffing box. Oil or vapors escaping through the release pop valve 58, and collected within tank chamber 59, can be discharged through pipe 25 and valve 62.

60 This description applies also to pop valve 12, in tank 13, valve 32 in tank 31, and to valve 63 in tank 64.

The condensing apparatus, E.

65 As this process of oil conversion is con-

tinuous, newly admitted oil to chamber 18, will in turn be "cracked" and changed in the apparatus into lighter and more volatile products, which will pass off in the form of vapors through goose neck 34 and 35. 70 These will enter the condenser head 37, of apparatus E, and be led down through the coil pipes 42, where condensation takes place, and the accumulated distillate will escape through valve 63, in trap tank 64, then pass 75 off through pipes 65 and 72, into collecting tank F, or it may be drawn off through pipe 66, and valve 67, or trapped in tank 90, then released through sight box 69, and collected in tank F. 80

A column 68, on which glass gages 70 and 71, are located, is mounted in close proximity to tank 43 of condensing apparatus E, in order to accurately record the height of accumulated oil in the lower part of coil pipes 85 42, or if trapped in tank 90, the glass gage 90', will indicate the height of oil therein.

Release valves 39 and 40, are mounted near the top of this column, which is connected to condenser head 37, by means of 90 pipe 38, as safety devices, in emergency, to relieve excessive pressure.

Collecting tank, F.

Distillates which are withdrawn from condensing apparatus E, can be accumulated in a suitable containing device such as collecting tank F, into which they can flow through pipe 72 and be withdrawn from the tank by means of pump 74 and pipe 73. 100

It may here be stated, that since this process of oil conversion depends upon subjecting the oil or oily vapors to very high temperatures considerably above their vaporizing or boiling points, and since this heat 105 cannot be applied without volatilizing in unconverted form, certain portions of the original oil or oily vapors which condense in the upper part of dome D, the trap tank 31, and pipe 33 provision is made for the 110 oil to be returned to the converter or supply system through pipes 75, and collecting chamber 76, pipes 29, 77 and 78', which latter takes into the neck pipe 20.

Inasmuch as the precise degree of temperature at which the plate 19, is maintained in practice, will largely depend upon and be varied by the gravity and boiling point of the oils to be treated, and other conditions, it will be sufficient to state that the temperature of the plate will be maintained at a cracking temperature of sufficient intensity to bring about the desired conversion of oil or oily vapors while under heavy vapor pressure throughout the system from the source 115 of supply through to the end of or beyond the condenser and liquid traps.

There are various parts of apparatus not as yet described, but which will be more fully enumerated in the several hereinafter 130

modes of operation; and while the above described apparatus may be modified greatly and yet be well adapted to carry out my process, I have designed and constructed the 5 converter so that it may be operated in the following manner.

Mode of operation (atmospheric.)

When converting very low boiling point 10 oils and vapors, or those above 65° B. under atmospheric conditions, and with only a light vapor pressure in the system, oil is admitted to container A, through pipe 1, the displaced air passing out through pipe 2, 15 at the top, until a sufficient quantity of oil is stored for progressive work.

The system is then supplied with oil 20 through valves 3 and 4, pipes 7 and 8, passing valves 9, and entering coils 15, of pre-heater B, interposed between the oil supply tank A, and converter C—D.

The oil circulating through these coils, is heated by the overflow hot oil from dome D, contained within the tank 16, then passes 25 through coil 17, in stack 50, where it receives an additional heating by means of the waste heat from furnace C, and is then passed through pipe 53, into cracking chamber 18, of the converter C—D, where a portion of it 30 is brought into contact with the intense cracking heat maintained in plate 19.

The oil is held at a uniform surface level 35 in dome D, as indicated by a dotted line X, for the purpose of supplying weight to hold the body of oil down against cracking plate 19, and also to provide a medium for the partial arrest of up-flowing converted and volatilized vapors, which are rapidly evolved by subjecting the oil to intensely 40 high temperatures.

As the vapors rise through pipe neck 20, to escape into the dome D, an intense agitation is carried on within this pipe, and which would cause undue and undesirable 45 agitation over the surface of oil at line X, if it were not checked by the perforated baffle plates 56, located within this neck.

As the oil rapidly becomes heated and volatilized, and would expand to unreasonable bounds if confined in the dome D, for 50 any prolonged length of time, the overflow pipes 75, are provided to carry off the surplus unconverted oil, which flows down through them, into connecting chamber 76, and out through pipe 24 and valve 81, sight box 82, pipe 25, and into pre-heater tank 16, from which it overflows at the top into pipe 27, and is accumulated in tank 26, from 55 which it may be withdrawn through pipe 28 and valve 83, by pump 84, and returned to reservoir tank A, by means of pipe 85.

This returned oil may then be supplied again to the converter through the system just described.

60 The overflow pipes 75, are attached to

base plate 96 (Fig. 6), and are located within the lower part of dome D, as to very effectually help in the evaporation of vapors which, having been generated in cracking chamber 18, rise through the oil in neck pipe 70 20, and that contained in the lower part of dome D, where they partially condense.

The heat of the contained oil within the dome D, drives them into vapor form again, and a certain portion is driven off from the 75 surface of the oil at X. The action takes place so rapidly within the dome, however, that some of the converted unvolatilized oils would be carried away in an ordinary single pipe drain, and to prevent this undesirable condition, the series of stand pipes 75, are so arranged on the base plate 96, and located at the bottom of dome D, as to make ample provision for the escape of such vapors from the increased surfaces presented 80 by the multiple of pipes and their inner superficial area.

This pipe arrangement is more clearly shown in Fig. 6, which affords a sectional view of the base plate 96, the stand pipes 75, 90 and the chamber 76, provided with the draw off pipe 24.

A certain portion of oil, having been "cracked," converted and vaporized, rises to the top of dome D, and passes out through 95 pipes 33 and 29, through valve 36, and goose-neck pipe 35, to condenser E, where, in the pipe coils 42, immersed in cold water, the vapors are reduced to condensate or distillates which pass out through pipe 66, valves 100 67, sight box 64, and pipe 72, into collecting tank F, from which the oil may be withdrawn through pipe 73, by means of pump 74, and delivered as required, through discharge pipe 85.

An important feature of pre-heater B, is the expansion tank 91, located above it, and also the vent pipe 86 above it, through which air and gases may pass to avoid vacuum or pressure within the tank 16, and which 110 would interrupt the proper flow of hot oil through the apparatus.

Another feature of importance embodied in this system is the series of water and sediment traps 88, 89 and 90, located at principal discharge points, so that any foreign matter or substances contained in the oil may precipitate out and not interfere with the perfect operation of the process.

Mode of operation (partial pressure.)

If a light or medium vapor pressure of not more than two or three atmospheres, or about 50 pounds to the square inch above that of the atmosphere, is required in a part 125 of the conversion system, when operating on low boiling point oils or oily vapors, the valve 36, in goose neck pipe 35, of the vapor line is closed, also valve 81, in pipe 24, of the hot oil overflow, under dome D, valve 77' in 130

pipe 77, and valve 4, in pipe 7, of the supply apparatus A; thus closing the system from pump 5, to pop valve 32, in tank 31, and pop valve 58, in tank 59.

- 5 The release pop valve 12, in tank 13, is set by means of the stem 12', to record a required pressure on the gage 11, and the pump 5, is operated to withdraw oil from the container A, and force it through pipe 10, against a vapor pressure greater than that which is maintained in the converter dome D, and at which pressure it will be released through pop valve 12, collected in trap tank 13, and by gravity flow, returned 15 to container A, through pipe 14.

When this supply system under pressure, is in operation, oil is admitted through pipe 8, and precision valves 9, into the pre-heater coils 15 and 17, and to the cracking chamber 18, by means of pipe 53, and oil inlet 53', (Fig. 2).

As the heat from plate 19, expands the oil into vapors and volatilizes the same, the converted vapors evolved therefrom are 20 checked by valve 32, and the overflow hot oil by pop valve 58.

By the proper adjustment of these valves with the stems 32' and 58', any required vapor pressure can be had within the container D, according to the nature and gravity of the oil to be operated upon and if such vapor pressure should be required at 30 50 pounds, as registered on gage 87, then the pop valve 12, should be set to resist a greater pressure, and the pump 5, operated to deliver oil at higher pressure into the system than that of the vapor pressure resistance it will meet with in the cracking chamber 18, and dome D, against which the 40 oil is forced by pump 5.

As a means instrumental in observing these pressures, gages 11 and 87, are provided in order to properly set the controlling springs or weights of the pop valves 45 in the oil and vapor discharge trap tanks 31 and 59.

Oil which is withdrawn from container A, and delivered into cracking chamber 18, by means of pump 5, is driven off in part 50 through dome D, in the form of vapors, and the balance in partially or wholly unconverted hot oil and condensed oily vapors.

That certain portion of oil which, having come in more or less contact with the heated plate 19, and becomes vaporized and cracked, rises through neck 20, and body of oil contained in the lower part of dome D, and expanding into the upper part of the dome, is driven off through pipes 33 and 29, pop 55 valves 32, trap tank 31, and goose neck pipe 34, then condensed under vapor pressure in the coils of apparatus E, from which the condensate or distillate flows through pipe 66, valves 67, sight 69, and pipe 72,

into collecting tank F, from which it may 65 be withdrawn as heretofore described.

That part of the unvaporized oil which overflows from the surface level X, in the dome D, is conducted through pipes 75, and into chamber 76, from which it is forced, by 70 the vapor pressure in dome D, through pipe 24, release pop valve 58, and is trapped in tank 59, from which it flows by gravity through pipe 25, sight box 82, pre-heater tank 16, and finally into receiving tank 26, 75 from which it may be withdrawn and returned to supply tank A, if desired.

Mode of operation, (high vapor pressure.)

When operating under high vapor pressure brought about by the expansion, vaporization and retention of oil and oily vapors in dome D, due to the applied heat to plate 19, as in a steam boiler, and it is desirable to place the entire system under high vapor 85 pressure for the purpose of converting high boiling point hydro-carbons by the application of intense heat and pressure above that of the atmosphere, valve 4, in pipe 7, is closed, and the release pop valve 12, in 90 tank 13, is set against a pressure sufficient for the pump 5, to deliver oil into the chamber 18.

The pop valve in tank 59, is opened wide, the valve 62, in pipe 25, and valve 81, in 95 pipe 24 is closed.

Pop valve 32, in tank 31, and valve 36 in pipe 35, are both opened wide to allow a passage of vapors in free communication with the condensing apparatus E.

Pop valve 63 in tank 64, is set against a vapor pressure by means of stem 63', and precision valves 67 are closed, while valve 77' in pipe 77 is opened, thus effectually sealing the system from pump 5, or source 105 of supply, to the pipes 65 and 72, at the end of the condensing apparatus E, which constitutes the discharge outlets for the condensate.

Valves 3 and 6, are then opened and pump 5, is operated to augment the flow of oil into the converter C—D, where the method of oil circulation and vapor collection, with the system under high vapor pressure, is the same as heretofore described when operating under atmospheric or partial and light vapor pressures.

In the discharge of overflow hot oil, however, through pipe 24, and pop valve 58, the accumulation of oil is registered in the 120 glass gage 92, located on collecting tank 59, from which tank it can be withdrawn through valve 62, as it may be required, to keep the oil at a uniform surface level at x, in dome D, and not to flood the trap tank 125 59. In like manner, the accumulated condensate in the lower part of coils 42, of condensing apparatus E, can be seen in glass

gages 70 and 71, located on column 68, and by means of pop valve 63, in tank 64, or by opening precision valves 67, in pipe 66, the oil in the lower part of the condensing coils 5 42, may be kept at a desired level. Distillates can also be accumulated under high vapor pressure in running tank 90, on which glass gage 90' is located, and released through valve and pipe 72' into tank F.

10 The sight boxes 82 and 69, are provided as a means of inspecting the discharge of oils from the system, and together with the glass gages and pressure registering gages, they form an important part of the visible 15 registry methods for determining the proper speed and flow of oil through the system.

Gases which may be present in the distillate, or fixed gases made in the process of conversion, can escape through pipe 93 and 20 valve 94, leading out from trap tank 64, or through pipe 93' in trap tank 90.

As the condensate collected in tank F, is of a complex nature, composed of converted and some partially converted original oil, it 25 may be withdrawn and treated by any of the common methods of fractional distillation or "topping," and the residue returned to the container A, if desired, for re-treatment as before.

30 From the foregoing disclosures, it is apparent that I have succeeded in formulating an apparatus and method of operation which is well suited to my process of oil and oily vapor conversion, and which is readily 35 adapted to the several objects in view, and that, as a result, I have made it possible with this apparatus, to convert inexpensive available hydro-carbon oils into products of greater commercial value, as well as to in- 40 crease the yield of petroleum and aromatic oils to meet market conditions.

As many changes could be made in the above described construction and methods of operation, and many apparently widely different embodiments of this invention could 45 be made without departing from the scope thereof, it is intended that all matter contained in the above description or shown in the accompanying drawings, shall be interpreted as illustrative and not in a limited 50 sense.

It is also to be understood that the language used in the following claims is intended to cover all of the generic and specific 55 features of this invention, and all statements of the scope of the invention which, as a matter of language, might be said to fall therebetween.

Having described my invention what I 60 claim as new and desire to secure by Letters Patent is:

1. In a device of the class described, the combination with a container for a body of oil embodying means for maintaining a por-

tion of the oil relatively separate and distinct from the main body of the oil, of means for subjecting said separate portion of oil to a local cracking and converting temperature, means for introducing superheated steam into said oil at the point where the 65 cracking temperature is applied, and means for collecting and condensing the generated vapors.

2. In a device of the class described, the combination with a container for a body of 70 oil embodying means for maintaining the lower portion of the oil relatively separate and distinct from the main body of the oil above, of means for subjecting said separate portion of oil to a local cracking and converting temperature, means for maintaining vapor pressure on said oil during the cracking operation, and means for collecting and condensing the generated vapors under pressure.

3. In a device of the class described, the combination with a container for a body of 80 oil embodying means for maintaining the lower portion of the oil relatively separate and distinct from the main body of the oil above, of means for subjecting said separate portion of oil to a local cracking and converting temperature, means for maintaining vapor pressure on said oil during the cracking operation, means for introducing superheated steam into the oil at the point where the cracking temperature is applied, and means for collecting and condensing the generated vapors under pressure.

4. In a device of the class described, the combination with a container for a body of oil embodying means for maintaining a portion of the oil relatively separate and distinct from the main body of the oil, of means for subjecting said separate portion of oil 90 to a local cracking and converting temperature, means for continuously introducing oil into said body of oil at the point where the cracking temperature is applied, means for maintaining a predetermined vapor 95 pressure on said body of oil, and means for condensing the generated vapors.

5. In a device of the class described, the combination with a container for a body of oil embodying means for maintaining the 100 lower portion of the oil relatively separate and distinct from the main body of the oil above, of means for subjecting said separate portion of oil to a local cracking and converting temperature, means for continuously 105 introducing oil and superheated steam into said body of oil at the point where the cracking temperature is applied, means for maintaining a predetermined vapor pressure on said body of oil, and means for condensing the generated vapors.

6. In a device of the class described, the combination with means for confining a

- body of oil, of means for subjecting a portion of said oil below the surface to a local cracking and converting temperature, means for continuously introducing oil into said body of oil at the point where the cracking temperature is applied, means for maintaining a predetermined vapor pressure on said body of oil, means for automatically drawing off any surplus unconverted oil to maintain said body at a substantially constant level, and means for condensing the generated vapors under vapor pressure.
7. In a device of the class described, the combination with means for confining a body of oil, of means for subjecting a limited portion of said oil at the lower part of said body to a local cracking temperature, means for continuously supplying preheated oil to said limited portion of oil where the cracking temperature is applied, means for drawing off oil from the upper portion of said body to maintain the level, and means for condensing the vapors of the converted oil.
8. In a device of the class described, the combination with means for confining a body of oil, of means for subjecting a limited portion of said oil at the lower part of said body to a local cracking temperature, means for continuously supplying preheated oil and superheated steam to said limited portion of oil where the cracking temperature is applied, means for drawing off oil from the upper portion of said body to maintain the level, and means for condensing the vapors of the converted oil.
9. In a device of the class described, the combination with a container for a body of oil embodying means for maintaining a flat shallow portion of the oil at the bottom relatively separate and distinct, of means for subjecting said flat shallow portion of oil to a cracking temperature, means for maintaining vapor pressure on the oil during the cracking operation, and means for condensing the generating vapors under pressure.
10. In a device of the class described, the combination with a container for a body of oil embodying means for maintaining the lower portion of the oil relatively separate and distinct from the main body of the oil above, of means for subjecting said separate portion of oil to a local cracking and converting temperature, means for continuously introducing oil and superheated steam into said body of oil at the point where the cracking temperature is applied, means for maintaining a predetermined vapor pressure on said body of oil, means for condensing the generated vapors, and means for maintaining a predetermined pressure on said vapors during condensation.
11. In a device of the class described, the combination with a converter, means for

supplying oil to said converter under pressure, means for heating the oil in said converter to a cracking temperature, a condenser connected to said converter, an adjustable automatic pressure control valve in said connection between said converter and said condenser, an outlet from said condenser, and an adjustable automatic pressure control valve in said outlet.

12. In a device of the class described, the combination with a converter comprising a lower cracking chamber of limited capacity, an upper expansion dome of greater capacity, and a connecting pipe or neck, of means for supplying oil and superheated steam to said cracking chamber, means for applying intense heat to said cracking chamber to convert the oil therein, means for maintaining a substantially constant oil level in said dome, and means for removing and condensing the vapors passing into said dome.

13. In a device of the class described, the combination with a converter comprising a lower cracking chamber of limited capacity, an upper expansion dome of greater capacity, and a connecting pipe or neck, of means for supplying oil and superheated steam to said cracking chamber, at a point where the cracking temperature is applied, means for applying intense heat to said cracking chamber to convert the oil therein, means for maintaining a substantially constant oil level in said dome, and means for removing and condensing under self-generated vapor pressure the vapors passing into said dome.

14. In a device of the class described, the combination with a converter comprising a thin horizontal cracking chamber having a flat bottom plate adapted to be raised to a high temperature and a central neck extending upwardly, an oil and vapor dome or receptacle into the bottom of which said neck leads, and means for supplying oil to said cracking chamber.

15. In a device of the class described, the combination with a thin horizontal cracking chamber having a flat bottom plate, means below said plate for heating it to a temperature sufficient to crack or convert oil in contact with it, a central neck leading upwardly from said cracking chamber, an oil and vapor dome above said chamber into the bottom of which said neck leads, and means for introducing oil and superheated steam into said cracking chamber through the top.

16. In a device of the class described, the combination with a thin horizontal cracking chamber having a flat bottom plate, means below said plate for heating it to a temperature sufficient to crack or convert oil in contact with it, a central neck leading upwardly from said cracking chamber, an oil and vapor dome above said chamber into the bottom of which said neck leads, means for introducing oil and superheated steam into

said cracking chamber through the top, means for drawing off vapors from the upper portion of said dome, and means for drawing off oil from said dome to maintain 5 the level therein.

17. In a device of the class described, the combination with a thin horizontal cracking chamber having a flat bottom plate, means below said plate for heating it to a temperature sufficient to crack or convert oil in contact with it, a central neck leading upwardly from said cracking chamber, an oil and vapor dome above said chamber into the bottom of which said neck leads, means for 10 introducing oil into said cracking chamber through the top, means for drawing off vapors from the upper portion of said dome, means for drawing off oil from said dome to maintain the level therein, and means in said 15 neck and dome to prevent the vapors rising up into said dome from unduly agitating the oil therein.

18. In a device of the class described, the combination with a thin horizontal cracking chamber having a flat bottom plate, means below said plate for heating it to a temperature sufficient to crack or convert oil in contact with it, a central neck leading upwardly from said cracking chamber, an oil and vapor dome above said chamber into the bottom of which said neck leads, means for introducing oil and steam into said cracking chamber through the top, means for drawing off vapors from the upper portion of said dome, and a series of draw off pipes extending from the bottom up into 25 said dome to the desired oil level.

19. In a device of the class described, the combination with a converter including a thin horizontal cracking chamber having a flat bottom plate, means below said plate for subjecting it to high heat, means for supplying oil and steam to said chamber through the top, and a metal in said chamber on said 40 plate having a fusing point below the cracking point of the oil to be treated.

20. In a device of the class described, the combination with a converter including a vapor dome, of a condenser, a pipe connection between the vapor space of said dome and said condenser controlled by a manually operable valve, a second pipe connection from the vapor space of said dome to said condenser, an automatic pressure regulating valve in said second connection, and means for controlling the discharge from 55 said condenser.

21. In a device of the class described, the combination with a converter, including a vapor dome of a condenser, a pipe connection between the vapor space of said dome and said condenser controlled by a manually operable valve, a second pipe connection from the vapor space of said dome to

said condenser, an automatic pressure regulating valve in said second connection, an outlet at the bottom of the condenser controlled by a manually operable valve and a second outlet from the bottom of said condenser having therein an adjustable automatic pressure regulating valve. 65

22. An apparatus of the nature disclosed, comprising in combination an oil supply tank and preheater, a converting chamber connected therewith and means for supplying and regulating the entry of unconverted liquids and oils to same, an overlying enclosed expansion dome for the collection of partly or wholly converted oily vapors in the upper part and unconverted oil in the lower part of said dome, means for the withdrawal and condensation of said vapors under vapor pressure, means to withdraw unconverted hot liquid oil from the lower part of said dome through a circumferentially arranged series of over-flow pipes attached to the bottom of said dome, means for utilizing said hot overflow oil in said preheater to heat incoming cold oil before entering said converting chamber and means for returning said oil with newly admitted oil to the action of intense heat in said converting chamber and vapor dome. 70 80

23. In a device of the class described, the combination with an oil converting chamber, of an expansion dome above said chamber and in communication therewith, means for drawing off converted vapors from the upper part of said dome, and a series of overflow pipes projecting into said dome at 100 the bottom to withdraw surplus unconverted oil and maintain its level. 90 95

24. In a device of the class described, the combination with an oil converting chamber, of an expansion dome above said chamber and in communication therewith, a circumferentially arranged collecting chamber below said dome, means for withdrawing converted vapors from the upper part of said dome, and a series of circumferentially arranged overflow pipes for unconverted oil 110 projecting upwardly into said dome and communicating with said collecting chamber.

25. In a device of the class described, the combination with an oil converter adapted to be raised to a cracking temperature, means for supplying oil to said converter, an expansion dome overlying said converter and in communication therewith, means for withdrawing converted vapors from said dome, means for permitting the overflow of hot unconverted oil in said dome to maintain the level therein and means for imparting heat from said overflowing hot oil to 120 the oil being supplied to the converter to preheat the same. 115 125

26. In a device of the class described, the

combination with an oil converter adapted to be raised to a cracking temperature, means for supplying oil to said converter, an expansion dome overlying said converter 5 and in communication therewith, means for withdrawing converted vapors from said dome, means for permitting the overflow of hot unconverted oil in said dome—to maintain the level therein, means for imparting 10 heat from said overflowing hot oil to the oil being supplied to the converter to preheat the same, and means for returning said overflowing oil to the converter with fresh oil.

27. In a device of the class described, the 15 combination with a thin horizontal cracking chamber having a flat bottom plate, means below said plate for heating it to a temperature sufficient to crack or convert oil in contact with it, a central neck leading upwardly from said cracking chamber, an oil and vapor dome above said chamber into the bottom of which said neck leads, and means 20 wardly from said cracking chamber, an oil and vapor dome above said chamber into the bottom of which said neck leads, and means

for introducing oil into said cracking chamber.

28. In a device of the class described, the 25 combination with a thin horizontal cracking chamber having a flat bottom plate, means below said plate for heating it to a temperature sufficient to crack or convert oil in contact with it, a central neck leading 30 upwardly from said cracking chamber, an oil and vapor dome above said chamber into the bottom of which said neck leads, and means for introducing oil into said cracking chamber, a collecting chamber around 35 said neck below said dome and overflow pipes extending from said collecting chamber into said dome and terminating at the desired oil level therein.

In testimony whereof I affix my signature. 40
JOSEPH H. ADAMS.
